UNITED STATES PATENT OFFICE.

GLEN E. CHAPIN, OF SAN ANTONIO, TEXAS.

WATER BICYCLE.

Application filed June 18, 1925. Serial No. 38,089.

To all whom it may concern:

Be it known that I, GLEN E. CHAPIN, a citizen of the United States, residing at San Antonio, in the county of Bexar and State 5 of Texas, have invented certain new and useful Improvements in Water Bicycles, of which the following is a specification.

This invention appertains to water vehicles and more particularly to a novel man- 10 ually propelled boat, constructed to simulate the appearance of a bicycle.

The primary object of the present invention is to provide a boat constructed to simulate the appearance of a bicycle em- 15 bodying a single central pontoon of a stream line shape with novel means for balancing the pontoon when the boat is in use, said balancing means being constructed on the principle of the bicycle steering wheel.

20 A further object of the invention is to provide a boat, of the so-called bicycle type including a stream line shaped central pontoon having a bicycle frame arranged on the upper face thereof including a pair of 25 handle bars, means for operating the boat including a propeller, and a rudder for guiding and balancing the pontoon, arranged at the front end of the pontoon and in a plane below the propeller, operated from the handle bars.

30 A further object of the invention is to provide a novel type of self-propelled boat of the so-called bicycle type, which can be readily operated in shallow water and owing 35 to the safety features thereof is particularly adapted for children, the said safety features embodying vertically swinging balancing planes normally arranged in a horizontal plane for engaging the surface of the water, the said balancing planes being operated from the handle bars of the boat 40 for working in conjunction with the steering and balancing rudders.

45 A still further object of the invention is to provide a novel boat of the above character, which will be durable and efficient in use, one that will be simple and easy to manufacture, and one which can be placed upon the market and afford a maximum amount of amusement for the user thereof.

50 With these and other objects in view, the invention consists in the novel construction, arrangement and formation of parts, as will be hereinafter more specifically de- 55 scribed, claimed, and illustrated in the accompanying drawings, in which drawings:

Figure 1 is a side elevation of one type of the improved boat of the manually pro- 60 pelled construction,

Figure 2 is a similar view of an engine 60 propelled boat,

Figure 3 is a side elevation of a type of boat particularly adapted for children,

Figure 4 is a top plan view of the same, 65 and

Figure 5 is a transverse section through the boat illustrating the arrangement of the balancing planes thereon.

Referring to the drawings in detail where- 70 in similar reference characters designate corresponding parts throughout the several views, the letter A generally indicates one type of the improved boat, which is particu- 75 larly adapted to racing or speed purposes.

The boat A is more particularly designed 75 for use by older persons and is provided with a novel balancing means as will be hereinafter more fully described. While in the specification, the term "bicycle boat" 80 has been used, it is to be understood that this expression is used in the sense that the boat is of a balancing type and is provided with a frame which simulates the appear- 85 ance of an ordinary bicycle construction. The boat embodies a single longitudinally 85 extending pontoon 10 of a stream line config- 90 uration including the front sharp edge 11. The pontoon can be formed in any desired way but is preferably constructed from sheet metal to provide an air and 90 water tight construction. The upper face of the pontoon supports a bicycle frame 12 including the usual rear fork 13 which is bolted or otherwise fixed at its lower end 95 to the pontoon 10 adjacent to the rear end thereof. The front of the frame embodies 95 the hollow handle bar post 14 which is riveted or otherwise fixed to the upper face of the pontoon 10 at the longitudinal center thereof. This handle bar post 14 prefer- 100 ably inclines rearwardly at an angle to the vertical and is connected to the support 12 by means of a connecting upper bar 15. Angularly extending bars 16 and 17 are con- 105 nected respectively to the upper end of the fork 13 and the post 14 at a point inter- 110 mediate its ends and the meeting point of these angularly extending bars 16 and 17 forms a bearing in which is rotatably mount- ed a crank shaft 18 to which is fixed suitable pedals 19. This crank shaft 18 has secured or otherwise affixed thereto a beveled drive

gear 20 which meshes with a beveled gear 21 keyed or otherwise secured to a drive shaft 22. This drive shaft 22 extends through the pontoon 10 and extends downwardly and rearwardly therefrom. The lower edge of the pontoon 10 at the rear end thereof supports a rigid keel 23 which serves as means for balancing the boat in water and this keel 23 has formed thereon a casing 24 through which the drive shaft 22 extends. A suitable drive propeller 25 is carried by a shaft for propelling the boat through the water. Rotatably mounted within the front steering column 14 is the handle bar post 26 which extends through the column 14 and through the pontoon 10. The lower end of the handle bar post 26 has secured thereto the downwardly and rearwardly guiding rudder 27 and it is to be noted that this rudder is disposed below the keel 23 and serves as an effective means for balancing the boat when the same is in use. The guiding rudder 27 can be braced by suitable brackets 28, which are secured thereto at a point intermediate the ends thereof. This bracket extends upwardly and forwardly at an angle and is secured directly to the handle bar post 26. Suitable collars 29 are connected with the column for engaging the bracket and to form a bearing therefor. The lower end of the column is supported by a suitable depending bracket 30. Secured to the upper end of the post in any desired way are the handle bars 31 which extend rearwardly toward the seat 32 which is of the ordinary bicycle type.

In use of the improved boat the user thereof operates the pedals 19 similar to a bicycle and the propeller 25 will effectively drive the boat through the water. The rudder 27 is used in the ordinary manner to steer the boat and is also used for balancing purposes similar to the front wheel of a bicycle and owing to the position of the rudder, the same readily serves for this purpose. As the boat gains speed, the same becomes more stable and there is less necessity for using the rudder 27 for balancing purposes. In view of the arrangement of the rudder all necessity of side pontoons is entirely eliminated and relatively great speed can be obtained with the boat in view of the little resistance offered thereby to the water.

In Figure 2 is disclosed a similar type of boat, which is generally indicated by the reference character B. The only difference between the type B and the type A, is that the pedals and crank shaft 19 and 18 are eliminated in the second form and a motor 35 substituted therefor. This motor 35 is arranged directly on the upper surface of the pontoon 10 and the rear end of the crank shaft 36 thereof is provided with a drive gear 37 which meshes with a drive

gear 38 on the propeller shaft. A control for the motor can be arranged on the handle bars as indicated by the reference character 39. In Figures 4 and 5 is shown a modified form of boat, which is particularly adapted to be used in shallow water and by small children. This form is generally indicated by the reference character C and embodies a pontoon 40 which is of a greater height and length than the pontoon 10 shown in Figures 1 and 2. The transverse sectional configuration of the pontoon 40 is however substantially the same as the pontoon 10 and includes the converging side walls 41 and the top wall or deck 42. This pontoon 40 is also provided with the front inclined leading edge 43.

Arranged upon the deck 42 of the pontoon 40 at a point intermediate its ends is a frame 44 constructed substantially the same as a bicycle frame and includes the rear fork 45 secured at its lower end to the pontoon and a bicycle handle bar column 46 which is extended through the pontoon at the front end thereof. The column 46 and the fork 45 are arranged in diverging relation and are connected by the longitudinally extending bar 47. The frame 44 supports a bearing 50 for the crank shaft 51 to which is secured the ordinary type of pedals 52. Secured to the crank shaft 51 in any preferred way is the drive bevel gear 53 which meshes with a bevel gear 54 secured to the propeller shaft 55. This propeller shaft 55 can be rotatably mounted in a suitable casing 56 which extends downwardly and rearwardly into the pontoon 40. The drive shaft 55 can be made in sections and the sections are connected by a suitable universal joint 57 and the lower section is rotatably mounted with suitable stuffing box 58 carried by the rear end of the boat. This rear section shaft has secured thereto in any desired way a screw propeller 59. Arranged slightly above the propeller 59 is the rudder 60 carried by the steering post 61 the upper end of which carries the laterally extending arms 62. It is to be noted that the post 61 is carried by a bearing 63 supported by brackets 64 secured to the rear end of the pontoon. Rotatably mounted within the steering column 46 is the handle bar post 65 the upper end of which is connected to any preferred type of bicycle handle bars 66. The lower end of the handle bar column 46 is extended through the bottom of the post and has secured thereto a steering rudder 67. A saddle seat 68 is arranged in rear of the handle bars and adjustably carried by the frame 44.

While the steering rudder 67 is disposed below the propeller 59 and the rear rudder 60, it is to be noted that the same is not disposed at a relatively great distance from

the bottom of the pontoon and thus while the rudder 67 can be employed for balancing purposes, I provide balancing planes 68 and 69 for this purpose. The balancing planes 68 and 69 are arranged on the opposite sides of the pontoon 40 at points substantially intermediate its ends and the forward ends of the planes are provided with hinge barrels 70 which receive outwardly extending 5 stub shafts 71 carried by the pontoon. The stub shafts 71 are arranged adjacent to the upper edge of the pontoon and the planes which are preferably formed of flat metal are adapted to be normally positioned in a 10 horizontal plane for engaging the upper surface of the water. Angle brackets 72 are secured to the upper surface of the balancing planes 68 and 69 adjacent to the inner forward corners thereof and these brackets have 15 secured thereto pull cables 73 which lead to radially extending arms 74 carried by the handle bar post 65. As clearly shown in Figure 4 of the drawings the arms 74 are formed on the handle bar post 65 at diametrically opposite points. The pull cables 20 73 are extended rearwardly from the brackets 72 and are crossed as at 74 and the terminals thereof are then secured to the end of the steering arms 62 carried by the 25 rear steering post 61.

By this construction when the handle bars 30 66 are turned, the rudders 67 and 60 will be turned synchronously and in the same direction, and one of the balancing planes will be lowered while the other will be raised. This 35 allows the easy turning of the boat and also insures the easy balancing thereof.

Changes in details may be made without departing from the spirit or scope of this invention, but what I claim as new is:

1. In a boat of the character described, a single longitudinally extending pontoon, a propeller carried by the rear end of the pontoon, means for operating the propeller, a steering and balancing rudder carried by the front end of the pontoon, flat balancing planes rockably carried by the pontoon at a point intermediate its ends normally arranged in a horizontal plane and means for operatively connecting the balance planes with the rudder. 40 45 50

2. In a boat of the character described, a single longitudinally extending pontoon, a bicycle frame carried by the upper face of the pontoon including a fork and a front handle bar column extending through the pontoon, a handle bar post rotatably mounted within the column, handle bars for the post, a rudder carried by the rear end of the pontoon, a propeller carried by the rear end of the pontoon, means for operating the propeller, flat balancing planes rockably carried by the opposite sides of the pontoon at a point intermediate its ends, a rudder carried by the lower end of the handle bar post adjacent to the forward end of the pontoon, and means for operating the rear rudder and the balancing planes from the handle bar post synchronously with the front rudder. 55 60 65 70

In testimony whereof I affix my signature.

GLEN E. CHAPIN.
